LIFT TRUCK

Arthur M. Barrett, Winnetka, Ill., assignor to
Barrett-Cravens Company, Chicago, Ill., a
corporation of Illinois

Application July 3, 1936, Serial No. 88,913

16 Claims. (Cl. 254—10)

This invention relates to lift trucks, and more particularly is directed to trucks of this type having a lower wheeled frame provided with any suitable type of steering means, and having an upper platform or frame which is adapted to be raised and lowered with respect to the lower frame, the upper frame or platform being adapted for picking tote boxes and the like from the floor, and then being raised in position in order that the truck may transport the load to any desired point.

The present invention broadly contemplates an improved and simplified design of truck, and in the main is an improvement over trucks of the type disclosed in my prior patents, Nos. 1,707,971, 1,773,925 and 1,803,688, of April 9, 1929, August 26, 1930, and May 5, 1931, respectively.

One of the main features of the present invention is that the truck of the present invention requires no release check for holding the upper frame or platform in raised position, although provision can be made for the attachment of such check means if it is desired by the operator.

However, the truck is designed for safe operation without the release check, by the provision of means whereby the truck may be moved under the load, and the platform raised into load supporting position and then retained in this position automatically until released by operation of a foot treadle or the like by the operator. After the operation of the foot treadle, it is necessary that the handle which controls the raising and lowering of the platform must be lowered to what would correspond to the end of the lifting stroke, which in turn effects the release of the upper frame from its latched position, and the operator then has the load under control by means of the handle in lowering the upper frame.

One of the primary objects of the present invention is to provide a sturdier and more economical construction, with special attention being directed to the rear axle construction which has been modified to produce a sturdy bearing support for guiding the upper frame in its raising and lowering movements, while at the same time preventing any removal of this frame from the lower frame.

Another feature of the present invention is the provision of improved latching means which is automatically engaged to latch the platform in raised position as the platform is raised by the steering handle, which latching means may be employed with or without the usual type of release check.

In connection with the latching means, one of the main advantages of the present construction is the provision of an arrangement whereby the latching means is engaged by a latch pin carried by the upper frame or platform in such manner that it positively secures the pin in latched position and prevents any accidental dislocation thereof. The latching means of the present invention is releasable only when the foot treadle member has been actuated and the handle then lowered to what would correspond to the end of the lifting stroke. Normal oscillation of the steering handle without prior actuation of the foot treadle will not result in release of the latching mechanism.

Other objects and advantages of the present invention will appear more fully from the following detailed description, which, taken in conjunction with the accompanying drawings, will disclose to those skilled in the art the particular construction and operation of a preferred form of the present invention.

In the drawings:

Figure 1 is a side elevational view of the latching mechanism employed in the present invention;

Figure 2 is a top elevational view of the detail parts of the latch control;

Figure 3 is an enlarged side elevational view of the latching mechanism, showing its operation with the platform in raised position;

Figure 4 is a sectional view, taken transversely across the rear axle of the truck, showing the improved rear axle construction; and

Figure 5 is a perspective view of one of the supporting crank arms shown in Figure 4.

Referring now in detail to the drawings, in Figure 1 I have provided a lift truck of more or less conventional design comprising a lower frame 5, having a crosshead at its front end journaling the steering shaft 6, and having a transverse rear axle shaft 7. The front axle shaft 6 is preferably carried by a steering yoke and in turn carries a suitable steering wheel 8, and corresponding transversely spaced wheels 9 are carried by the rear shaft 7.

Supported at the front end of the frame 5 is a crosshead 10, which is in the form of an inverted U, and is provided with a centrally located bearing for the vertical pivot of the steering yoke which supports the shaft 6 and the steering wheel 8. Either one or two steering wheels may be provided.

The journal bearing plate 12 for the steering yoke carried by the pedestal or crosshead is pro-

55

vided with forwardly extending ears 13 spaced apart to form a yoke, through which ears extends a cross pin 14, pivotally supporting the steering and lifting handle 15. It is apparent 5 that the ears 13 are offset in relation to the axis of the steering wheel pivot and are disposed forwardly thereof. It will be apparent that the steering handle 15 is thus mounted for oscillating movement in a generally forward and rearward direction. The handle of course is also capable of swinging laterally, or to one side or the other of the longitudinal axis of the truck, to steer the wheel or wheels 8.

Mounted upon the lower frame 5 is a lifting frame 16, having side members which overlie the side members of the supporting frame 5. Near the front end thereof the side members are connected by a cross beam 17, which is preferably in the form of a channel-shaped member 20 to the web surface of which is secured an angle member 18 forming a platform stop for limiting the forward position of the platform or load which is to be carried upon the frame 16.

The forward end of the side members forming 25 the frame 16 have pivotal connection at 19 with suitably disposed links 20 for guiding the raising movement of the upper frame or platform. The links 20 are pivoted at their lower end to the side members of frame 5 adjacent the rear 30 end portions 22 of the crosshead 10, as indicated at 23. By pulling forward on the lifting frame, it will be apparent that the platform 16 will be raised by the clockwise rotation of the links 20 about the pivot 23, the platform moving upwardly and forwardly.

Considering now the connections between the lifting handle 15 and the frame 16, I have provided a yoke member 25, which is substantially V-shaped, and the separated rear ends of the 40 yoke are adapted to pass through the vertical flange 26 of the cross beam 17. These ends carry rounded heads 27 as shown in dotted lines in Figure 1, which are secured in place by suitable nuts screwed onto the rear ends of the yoke. 45 The heads 27 bear in the angle formed in the cross beam 17, and form rocker bearings for the yoke, to permit its forward end to swing slightly, thereby preventing binding during the operation of raising or lowering the lifting frame.

50 At its forward end, the yoke 25 carries a double link 28, comprising portions 29 and 30 rigidly connected together and disposed at right angles to each other. The portion 29 has a horizontally directed opening 32 therein which receives the 55 end of the yoke 25, while the portion 30 has a vertically directed opening which is adapted to receive a shackle member 33 pivoted on the transverse pivot 14 which supports the operating handle 15, and which is in the form of a bell-crank, the opposite end away from the pivot 14 60 being tapered and provided with a lug or tooth 34 adapted to be engaged by the hook portion 35 of a member 36 mounted on the handle 15 by means of the pivot 37. The latch 36 is provided 65 with a thumb piece 38 in order to accommodate its release from the shackle member 33.

In the operation of raising the platform lifting frame 16, the steering handle 15 is moved in a clockwise direction about the pivot 14, which results in forward movement of the shackle member 33, and consequently a forward and upward pull upon the yoke member 25. This exerts a corresponding forward and upward pull on the frame members constituting the platform 16, and 70 the platform 16 moves forwardly and upwardly 75

about the pivot 23 and the pivot formed by the rear axle shaft 7.

Considering now Figures 2 and 3 in detail, the forward end of the lifting frame 16 is provided intermediate the sides thereof with a pair of forwardly extending parallel strips 40 and 42, which may be welded or otherwise suitably secured thereto, and which at their forward ends are provided with means for supporting the latch pin 43 therebetween, the pin being held against displacement by means of the cotter key 44 as shown in Figure 3.

Mounted upon the pedestal support or cross head 10, which is provided with the rearwardly extending spaced ears 45, is the latching mechanism shown in detail in Figures 2 and 3. Supported at the outer ends of the ears 45 is the pivot pin 46, which is adapted to receive therebetween a treadle member generally indicated at 47, and of generally Z-shape. The treadle member 47 is provided with a forwardly extending treadle portion 48, and with rearwardly extending arms 49 carrying pivot pin 50 at their outer ends. Pivoted on the pin 50 between the arms 49 is the member 52, which has a counterbalancing plate-like portion 53 normally holding the member 52 in the position shown in full lines in Figure 3. In this position, the member 52 has the angularly extending facing edge 54 adapted to engage on the top surface of the latching jaw 55, which 25 latching jaw is provided with a rearwardly extending portion 56 mounted on the pivot pin 46. The latching jaw 55 is provided with a downwardly curved tip portion 57 adapted to form a camming surface for guiding the latch pin 43 30 upwardly along the upper surface of the jaw 55, and is also provided with a notch or latch retaining recess 58 adapted to receive the latch pin 43.

The jaw 55 is provided with a downwardly projecting boss 59 at its lower side, having a recessed opening 60 forming a seat receiving one end of the spring 62, the opposite end of the spring 62 being biased in a seat 63 formed in a projecting boss 64 of the treadle member 47. By reason of this spring connection, the treadle member 47 tends to rotate in a counterclockwise direction with respect to the pivot 46, while the jaw member 55 tends to rotate in a clockwise direction. As a result, the edge 54 of the member 52 is 40 pressed downwardly into pressure engagement with the upper inclined surface of the jaw member 55, normally overlying and protecting the notched recess 58 of the jaw member 55. The above described latch assembly comprising the parts 47, 52 and 55 has a floating or free swinging mounting on the supporting pin 46. Hence, this latch assembly is free to swing downwardly by gravity to a normal position in which a stop surface 61 at the lower front edge of the member 47 abuts against the back surface of the cross head 10. In such normal position of the latch assembly, the parts thereof are so disposed, relative to the path of travel of the latch pin 43 on the lifting frame, that during the lifting operation this latch pin moves upwardly over the rear surface 57 of the latch jaw 55 and into engagement with the rear edge of the locking member 52. 50 55 60 65 70 75

Referring now to the operation of the latch mechanism, the lifting frame is raised by a downward stroke of the handle 15, and in such lifting movement the latch pin 43 on the lifting frame swings upwardly over the rear surface of the latch jaw 55 and into engagement with the rear edge of the locking member 52, as above de- 75

scribed. Continued forward motion of the latch pin 43 in abutment with the rear edge of said locking member 52 causes the latter to swivel forwardly or inwardly around its pivot 50 in a counterclockwise direction. In this inward swinging motion, the lower lip 65 of the member 52 exerts a camming pressure on the upper surface of the jaw member 55, thereby causing a relative spreading motion between the treadle member 47 and said latch member 55, and accommodating continued inward motion of the locking member 52 toward the final position indicated approximately in dotted lines in Figure 3. This relative spreading motion is yieldably opposed by the spring 62. In the final movement of the parts, the latch pin 43 rides beyond the shoulder 67 of the latching jaw 55 so that this jaw member can swing upwardly under the action of the spring 62 and hook its latching recess 58 around the back side of the latching pin 43. Also, the locking member 52 assumes the final position indicated in dotted lines with the tip end 65 thereof bearing against the upper lateral surface of the latch pin 43. The locking member 52 is held in this position, pressed against the pin 43, by the pressure of the spring 62, and also by the weighted portion 53 of said member, which tends to rotate the latter in a clockwise direction about the pivot 50. It is also to be noted that the arms 49 of the member 47 are provided with stop surfaces 66 which are abutted by the weighted portion 53 to limit the counterclockwise rotation of the member 52, thereby insuring that said locking member will be pressed against the latch pin 35 when in this final position through the action of the spring 62 tending to force the members 52 and 55 toward each other.

In this position, with the latch pin 43 disposed in the notch or recess 58 of the jaw member 55, and the member 52 bearing against the upper surface thereof, no disengagement of the pin 43 from the latching means is possible, even though the lifting handle 15 be oscillated rearwardly, tending to allow the member 16 to lower under gravity, due to the release of pulling engagement on the yoke 25. As a result, regardless of movement of the handle 15 into any upper, lower, or sidewise position, the platform remains latched in raised position, and the truck can be moved to any desired location without the danger of lowering the platform or upper frame due to movement of the handle 15. When it is desired to lower the platform 16, the operator must first step on the treadle member 48. This produces clockwise rotation of the treadle member, and results in an upward movement of the arms 49. As a result, the pivot pin 50 is lifted upwardly, and due to the counterbalance 53 on the member 52, the member 52 also rotates in a clockwise direction and returns to its normal position with the surface 54 thereof engaging the upwardly inclined surface of the jaw member 55, and overlying the jaw member and the recess 48.

When the treadle member has been thus actuated, and the member 52 restored to its normal position, there is no means engaging the upper surface of the pin 43 restraining it within the notch 58. However, due to the fact that the notch 58 has a curved rearward surface which extends over and beyond the center of the pin 43, the platform still will not be capable of being lowered by itself, but the latching means is now conditioned for release of the pin 43 upon movement of the handle 15.

If the handle 15 is now lowered to a position

corresponding to the end of the lifting stroke, the handle upon depression will allow the entire latching assembly to swivel about the pin 46, the rear end of the member 55, indicated at 57, moving downwardly in a counterclockwise direction with respect to the pivot 46. This moves the notch 58 downwardly, until the center of the pin 43 moves above the lip of the notch 58, indicated at 67. As a result, the pin 43 can then move outwardly between the members 55 and 52, along the overlying surfaces thereof, and the platform or upper lifting frame can be lowered under control of the handle 15. Thus, as the handle is slowly released, the pin 43 pulls outwardly between the member 55 and 52, separating these members, and permitting the frame or platform 16 to move downwardly under gravity and under the control of the operator through the handle 15.

It is thus apparent that I have provided a novel type of latching means, capable of automatic engagement upon lifting of the upper lifting frame, and adapted to restrain the platform in raised position regardless of movement of the steering and control handle unless the treadle member 47 is first operated to condition the latching means for release of the pin upon further movement of the handle 15. The construction is relatively simple, composed for the most part of castings, which can be easily assembled, and which require no accurate machining operations. Thus a simplified and economical design of latching mechanism is provided which is positive in operation and employs relatively few moving parts.

Considering now in detail Figures 4 and 5 in connection with the rear axle construction shown in Figure 1, the present invention contemplates a construction which, while of the general form used in previous lift trucks of this design, has incorporated therein several differences which not only reduce the manufacturing cost, but which produce a better and sturdier construction.

In this embodiment of the invention, the rear links and the upper part of the rear axle are embodied in one member. The axle shaft 7, which has the wheels 9 journaled thereon adjacent opposite ends thereof, is itself journaled for rotation in the side members 10 and 12 of the lower frame 5.

Secured to the axle shaft 7 inwardly of the frame members 12 are a pair of U-shaped clamps 73, formed of flat strips of metal bent into U-shape, and having the extending parallel portions 74 adapted to be clamped together by means of the bolt 75 passing therethrough. This frictionally clamps the member 73 to the axle shaft, and if desired the shaft may be flattened at one portion to receive the flattened surface of the bolt 75 in order to positively prevent rotation of the member 73 with respect to the shaft. The shaft, of course, is free to rotate with respect to wheels 9.

Mounted upon the external surface of the U-shaped portion of the member 73 is a crank arm 76, comprising a right angle member formed of stock turned at one end to provide a reduced projecting stud 77, and bent cold in a die to produce the right angle form shown. The opposite end of the member 76 is welded or otherwise suitably secured to the member 73, as indicated at 78. The extension 77 of the shaft or crank portion 76 of the axle construction enters through the upper end of a link 79 mounted at its opposite end on the shaft 7, and then extends into the side member 80 of the supporting or lifting frame 16. Preferably the projection 77 of the member 76

76 extends flush with the outer lateral surface of the side frame members 80, in order to eliminate any projections or the like on the sides of the upper frame.

5. It will be apparent that by this construction the upper frame 16 is positively connected to the lower frame through the members 76 and the clamping portions 73 thereof, and also that the load on the platform or upper frame 16 is supported by these members which bear, on the horizontally extending outturned portions, within the angle formed by the angle member 82 secured transversely between the side frame members 80.

15. It will therefore be apparent that upon lifting of the frame 16 by means of the handle 15, the rear end of the frame will move upwardly and forwardly about the axle 7 as a center, and any load upon the frame will be supported by the 20. crank arms 76. By the provision of the link 79, the free ends of the arms 76 are prevented from bending inwardly, and in effect a substantially U-shaped support comprising the members 73, 76 and 79 is disposed about each of the wheels and 25. engages in the angle bearing member 82 at the rear end of the frame 16 for supporting the same as it is raised in position.

Of course, if desired the members 76 and 73 might be formed integral as a casting, clamped 30. to the axle shaft in the same manner, but I have found that the welding of the stock 76 to the bent strip 73 serves the same purpose and is equally as effective for supporting the load on the platform during the raising movement.

35. It is thus believed obvious that the axle construction herein provided is considerably simplified over the constructions shown in my aforementioned patents, and also possesses distinct advantages of design and construction as far as ease of manufacture and economy is concerned.

40. While I am aware that various changes in the construction, design and fabrication of the various parts constituting the features of the present invention are possible, I do not intend to 45. limit the present invention to the specific illustrated embodiment thereof, but only in so far as defined by the scope and spirit of the appended claims.

I claim:

50. 1. In combination, a lift truck comprising a frame, a platform carried by said frame, means including a handle pivoted at one end of said frame for raising and lowering said platform, a latch pin carried by said platform, latching means 55. pivotally mounted on said frame for receiving and retaining said latch pin when said platform is raised including means for locking said pin in platform-raising position, and means carried by said latching means for moving said locking 60. means into inoperative position while leaving the said latching means in operative position, said latching means being constructed and arranged to then release said pin upon a further lift of the platform by said raising means.

65. 2. In combination, a lift truck comprising a frame, a platform carried by said frame, means including a handle pivoted at one end of said frame for raising and lowering said platform, a latch pin carried by said platform, latching 70. means pivotally mounted on said frame including means for receiving and locking said latch pin when said platform is raised, and means for releasing said locking means while leaving the said latching means in operative position, said 75. latching means being constructed and arranged

to then release said pin upon a further lift of said platform by said raising means, said raising means being effective to release said pin only upon prior actuation of said releasing means.

3. In combination, a lift truck comprising a 5 frame, a platform carried thereby, means including a control handle mounted on said frame for raising and lowering said platform with respect to said frame, latching means operable upon raising of said platform for locking said platform in 10 raised position, and means operable independently of said raising and lowering means for setting said latching means in position to permit release of said platform upon a further lift of said platform by said raising means.

4. In combination, a lift truck comprising a wheeled truck frame, a platform carried thereby, means for moving said platform upwardly and longitudinally with respect to said frame into raised position, latching means for retaining said 20 platform in raised position including a part moved by raising of said platform into position to prevent release of said latching means, and release means independent of said moving means for returning said part out of said position while retaining said platform latched in raised position, 25 said platform moving means being operable for releasing said platform from said latching means only upon prior actuation of said release means.

5. Latching means for receiving and retaining 30 a load-carrying platform of a lift truck in raised position, said platform having a latch pin, said latching means comprising a support, a first jaw member pivotally mounted on said support, a treadle member pivoted coaxially of said jaw 35 member on said support and including arm portions extending over said first jaw member, a second jaw member pivotally mounted between said arms and normally overlying the upper surface of said first jaw member, a latch pin retaining 40 recess in the upper surface of said first jaw member normally protected by said second jaw member, spring means between said first jaw member and said treadle member urging said jaw members into engagement, said second jaw member being rotated by entrance of the latch pin 45 between said jaw members and into said recess into a position retaining said pin in said recess, and means on said second jaw member operable upon rotation of said treadle member moving said 50 arms away from said first jaw member for restoring said second jaw member to its normal position overlying said upper surface of said first jaw member.

6. Latching means of the class described for 55 holding a load supporting platform in raised position, said platform having a latch pin, said means comprising a pair of latching jaws, spring means normally urging said jaws together, one of said jaws having a latch pin retaining recess 60 and the other of said jaws being independently rotatable with respect to said one jaw, means for raising said platform whereby said pin is forced between said jaws and engaged in said recess, said other of said jaws being rotated into position to hold said pin in said recess, and means pivoted coaxially of said one jaw for restoring said rotatable jaw to initial position independently of movement of said platform.

7. Latching means for supporting the lifting 70 platform of a lift truck in raised position comprising a pair of latch members normally maintained in superposed position, the upper latch member being pivotally mounted for movement independently of the lower member, a latching 75

recess in one of said members adapted to receive a latch pin carried by said platform and forced between said members when the platform is raised, the other of said members being pivoted into overlying engagement with said pin by movement of said pin into said recess, means for restoring said other of said members to normal superposed position, and means operable when said platform is to be lowered to enable said latching members to rotate into position to disengage said pin from said recess, said pin moving outwardly between said members upon lowering of said platform.

8. The combination, with a lift truck having a platform adapted to be raised and lowered, and operating means for raising and lowering said platform, of a latch pin carried by said platform, a pair of latching members having a pin-retaining recess in one of said members, the other of said members being pivotally mounted in position normally overlying said recess, said pin rotating the other of said members out of overlying position and entering said recess when said platform is raised, spring means urging said other of said members into position to hold said pin in said recess, and means operable independently of said platform-operating means for restoring said other of said members into normal overlying position, so that a further operation of said platform operating means will first permit said latching members to rotate into a position to release said pin from said recess, and upon release of said platform operating means will permit the lowering of said platform and the simultaneous movement of said pin outwardly from between said jaw members.

9. Latching means for a lift truck having a lifting platform, comprising a pivotally mounted latch member having a latch-pin receiving recess, pivotally mounted means normally overlying said recess, spring means normally urging said last-named means against said latch member, a latch pin carried by said platform and adapted to rotate said pivotally mounted means away from said latch member and to engage in said recess upon raising of said platform, said pivotally mounted means being spring pressed against said pin after said pin engages in said recess, means for raising said pivotally mounted means away from said pin to restore said pivotally mounted means to its normal position overlying said recess, and means operable when said platform is to be lowered for releasing said pin from said recess and into position to pass outwardly between said latch member and said pivotally mounted means as the platform is lowered.

10. In a lift truck of the class described, a frame, a platform mounted on said frame, a holding latch pin at one end of said platform, a latch having a latching recess and pivotally mounted on said frame adjacent said end of said platform, a treadle member conjointly pivoted with said latch and having a portion overhanging said latch, a locking member pivotally supported by said overhanging portion and normally overlying said recess, spring means normally urging said locking member into said latter position, and means for raising said platform and moving said latch pin against said locking member to pivot said locking member into position above said recess to permit said pin to enter said recess, said spring means urging said locking member into engagement with said pin after said pin has entered said recess.

11. In a lift truck having a truck frame, an axle

extending transversely through said frame, wheels journaled at the opposite ends of said axle, a platform carried by said frame, and means for guiding and supporting said platform with respect to said axle comprising rock arms rigidly secured to said axle adjacent said wheels, integral out-turned ends on said arms having reduced journal portions, links between the ends of said axle and said platform, and means in said links and said platform for receiving the journal portions of said arms.

12. A rear axle construction for a lift truck of the type having an upper frame and a lower frame, comprising an axle shaft journaled transversely in said lower frame, wheels on said shaft adjacent opposite ends thereof, links mounted at one end on the ends of said shaft, and rock arms secured to said shaft between said wheels and including end portions journaled in said upper frame and in the opposite ends of said links.

13. Means for supporting and guiding the upper frame of a lift truck with respect to the lower frame, comprising an axle shaft journaled in the lower frame, wheels mounted on the ends of said shaft and rotatable thereon, an angle bearing member extending transversely across the upper frame at one end thereof above said shaft, vertical side flanges forming a part of said upper frame, and U-shaped means having the ends thereof secured to said axle shaft on opposite sides of each of said wheels and having bearing engagement with said angle member, said means having laterally extending stud portions engaging said side flanges at opposite ends of said bearing member to connect said upper frame thereto through to said shaft.

14. Means for supporting and guiding the upper frame of a lift truck with respect to the lower frame, comprising an axle shaft journaled in the lower frame, wheels journaled on the ends of said shaft, an angle bearing member extending transversely across the upper frame at one end thereof above said shaft, side flanges forming the edges of said upper frame, and U-shaped means having the ends thereof mounted on said axle shaft on opposite sides of each of said wheels and having bearing engagement within said angle member, said means having laterally offset studs engaging said side flanges to connect said upper frame therethrough to said shaft, each of said U-shaped means comprising a planar link member mounted at one end on said shaft, and an L-shaped bracket secured at one end to said shaft and having its opposite end passing through the opposite end of said link member and terminating in one of said offset studs.

15. In combination, a lift truck frame, a platform thereon, means pivoted at one end of said frame for raising and lowering said platform with respect to said frame, latching means on said frame including a pair of pivotally mounted latching members, a latch pin carried by said platform and movable between said members upon raising of said platform into latched position therebetween, and means for pivoting one of said latching members into unlatched position while said other latching member retains said pin against release, said latter latching member being constructed and arranged to then release said pin upon a further lift of the platform by said raising means.

16. In a lift truck of the class described, the combination of a main frame mounted on rear wheels and on a laterally steerable front wheel, a lifting frame mounted on said main frame for

upward movement relative thereto, an operating handle pivotally mounted on said main frame for vertical swinging movement, and also for lateral swinging movement to steer said front wheel, a raising mechanism actuatable by downward swinging movement of said handle to raise said lifting frame, said raising mechanism and said handle also being operative to lower said lifting frame with a gradual movement exercised through controlled upward movement of said handle, latch mechanism comprising a latching hook carried by one of said frames and on the back side of which is defined a latching recess, a latching pin carried by the other of said frames

and adapted to have hooked engagement within said latching recess whereby to establish a latched relation capable of retaining said lifting frame in elevated position, and a locking member movable into position to block relative separation between said latching pin and said latching recess so as to prevent accidental lowering of said lifting frame irrespective of the movement of said handle into different positions, said locking member being manually releasable when it is desired to lower said lifting frame through the instrumentality of said handle. 10

ARTHUR M. BARRETT.
